UNITED STATES PATENT OFFICE

FLOYD D. ROAN, OF NEWLIN, TEXAS, ASSIGNOR TO F. D. ROAN MACHINE COMPANY, OF NEWLIN, TEXAS, A CORPORATION OF TEXAS

COTTON CLEANER

Application filed April 23, 1929, Serial No. 357,550. Renewed September 23, 1930.

This invention relates to apparatus for cleaning cotton.

The primary object of the present invention is to provide a cotton cleaning machine which will effectively remove from the cotton all leaves, twigs, and dirt without whipping the cotton or breaking the fiber or stringing the cotton.

Another object of the invention is to provide an apparatus for cleaning cotton which operates by driving air through the cotton as the same is passed over and agitated on cleaning screens, instead of making the cotton cleaner a part of an air line for extracting the dirt from the cotton by suction as is done according to the present methods.

The invention broadly contemplates the provision of a casing of elongated construction having an inlet or feed hopper at one end and a discharge opening or port at the opposite end, there being suspended in the casing between the ends, a plurality of transverse concave screens, in each of which is positioned a beater drum provided with a plurality of relatively long whipping fingers. In the upper part of the casing over each of the beater drums is mounted a rotary fan which drives a blast of air directly downwardly upon the underlying drum, forcing dirt from the cotton in the underlying screens downwardly therethrough into an underlying receiving structure. The dirt receiving structure has a valved outlet which is timed to open at intervals for the discharge of the dirt removed from the cotton.

The invention will be best understood from a consideration of the following detailed description taken in connection with the accompanying drawing forming a part of the present invention with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a view partly in longitudinal section and partly in side elevation of the cot-

ton cleaning machine embodying the present invention;

Figure 2 is a diagrammatic top plan view of the same;

Figure 3 is an elevational view of a portion of one of the curtains in the machine.

Figure 4 is a sectional view taken on line 4—4 of Figure 1.

Figure 5 is a detailed sectional view on line 5—5 of Figure 1.

Referring to the drawing in detail, the numeral 1 indicates the side frames of the machine embodying the present invention, these frames being in spaced parallel relation as shown and forming the skeleton for the side and end walls 2 and 3 respectively, for the raised or domed top 4 and the depending dust and trash receiving hopper 5 which hangs from the under side thereof, as shown.

At one end of the machine there is formed a hopper 6 which opens through the end wall to the interior of the structure and at the opposite end the wall is provided with an outlet opening 7.

Extending longitudinally of the frames 1 is a series of concave screens 8 which hang from the lower beams 9 of the frames and extend transversely of the machine, as shown. Above each of the concave screens each beam 9 carries a bearing 10 in which is supported one end of a cylinder shaft 11, each of which carries a beater cylinder 12, which is formed by extending through the shafts a plurality of rods 13 which project radially therefrom providing beater fingers which, when the cylinders are rotated, sweep over the underlying arcuate screen. These beater fingers from the shafts outwardly are of substantial length, preferably approximately ten inches, so that ample space is provided between the shafts and the underlying screens to prevent jamming or packing of the cotton and to allow the air forced down against the cylinder by the fans hereinafter described, to have free passage through the cotton and screens.

The top beam 14 of each frame member carries at a point above each of the bearings 10, an upper bearing 15 and extending transversely of the machine and supported in these

bearings are fan shafts 16, each of which carries a cylinder fan 17. The top 4 above each of the cylinder fans is provided with an air inlet opening 18 through which air can be supplied to the interior of the machine by the fans. These fans are of the usual construction, comprising a series of blades 17^a extending longitudinally of and projecting radially from the shafts 16 and being secured thereto by the strap brackets 17^b which are carried by the shafts.

The tops of the casings in which the fan blades are housed are provided with suitable air inlet apertures 17^c through which air is drawn to be blown downwardly through the outlet chutes 17^d which open tangentially from the casings 17.

Suspended transversely of the machine beneath each of the cylinder fans 17, are transverse sheets or curtains 19 made up of a plurality of strips of flexible material such as belting or the like, the lower ends thereof terminating at a point just above the beater fingers 13 of the underlying cylinder. These curtains are suspended from the fan structures as shown in Figure 1, from a point forwardly of the vertical plane in which the shafts 11 and 16 lie so that their lower edges will be in a plane slightly below the tips of the beater fingers 13 when they reach the highest point in the period of their rotation. These curtains prevent cotton being carried around by the fingers 13 and also serve to force the air drawn downwardly from the cylinder fans to pass beneath the beaters and through the screens instead of being partially deflected to pass over the beaters.

At the lowermost point of the hopper 5, there is positioned a rotary valve 21 which is designed to be intermittently operated for the periodic discharge of the dirt collected in the lower part of the hopper from the cotton passing through the machine. The rotary valve as shown in Figures 1 to 4 is of semi-cylindrical formation and is designed to be intermittently rotated as above described so that a complete rotation thereof will be divided into four periods in two of which half of the hopper discharge opening will be uncovered and between these two periods the opening will be completely closed. No particular means has been shown for creating the intermittent rotary movement of the valve as any number of methods may be employed for the performance of this function.

In the operation of the present machine any suitable means may be employed for rotating the beater cylinders 12 and the fans 17, as for example, the shafts 11 of the beater cylinders may be provided with pulleys 20 in the manner shown, with belt connections therebetween so that all of the cylinders will be made to rotate in the same direction. It will be readily seen from the foregoing that

as the cotton after passing through the boll breaking machine is discharged into the hopper 6, it will first fall upon the nearest one of the screens 8 where it will be caught by the fingers of the first cylinder 12 and discharged therefrom after thorough agitation into the next screen and so on to the other end of the machine from which it will be discharged through the opening 7. During the passage of the cotton through the machine over these screens it will be thoroughly shaken or agitated to permit the air blown downwardly thereon by the fans 17 to pass therethrough and extract all of the dirt, dust, twigs, etc., therefrom.

Having thus described my invention, what I claim is:

1. In a cotton cleaning machine, a closed casing, a plurality of concave screens extending transversely of the casing, beater cylinders operating in each of said screens to move the cotton from one end of the casing to the other over the screens, a dirt receiver beneath said screens, fans in the upper portion of the machine for delivering air downwardly against each of said cylinders for blowing the dirt from the cotton, and a curtain depending from each of said fans to a point in close proximity to the beater lying therebeneath and extending transversely of the casing whereby to divide the casing into a series of compartments.

2. In a cotton cleaning machine, a closed casing, a plurality of concave screens extending transversely of the casing, beater cylinders operating in each of said screens to move the cotton from one end of the casing to the other over the screens, a dirt receiver beneath said screens, fans in the upper portion of the machine for delivering air downwardly against each of said cylinders for blowing the dirt from the cotton, a curtain depending from each of said fans to a point in close proximity to the beater lying therebeneath and extending transversely of the casing, said curtain dividing the casing into a series of successive compartments, and a rotary discharge valve in the lower portion of said dirt receiver designed to intermittently operate for the removal of dirt therefrom.

3. In a cotton cleaning machine of the character described, a cotton beating structure including a plurality of concave screens and rotary beaters working therein, fan means for delivering an air blast downwardly from the beaters and screens, curtain means depending from said fan means, the lower end portions of said curtain means terminating adjacent the periphery of said beaters, a dirt hopper beneath said screens, and an intermittently operated rotatable dirt receiver mounted in the hopper.

4. In a cotton cleaning machine of the character described, a closed casing, a plu-

rality of concave screens extending transversely of the casing, rotatable beaters for each of said screens, individual fan means adapted to deliver an air blast against each of said screens, curtain means depending from said fan means and extending transversely of said casing whereby to divide said casing into a series of successive compartments, a depending dirt hopper beneath said screens, and a rotatable dirt receiver for intermittently removing dirt from said hopper.

In testimony whereof I hereunto affix my signature.
